UNITED STATES PATENT OFFICE.

EDMUND W. ZEH, OF NEWARK, NEW JERSEY.

POWER TILE PRESS.

Application filed October 23, 1920. Serial No. 418,891.

To all whom it may concern:

Be it known that I, EDMUND W. ZEH, a citizen of the United States, and a resident of Newark, in the county of Essex and State of New Jersey, have invented new and useful Improvements in Power Tile Presses, of which the following is a specification.

This invention relates more especially to tile presses in which an upper die cooperates with a lower die comprising a central portion and a frame around said central portion movable independently thereof, said frame forming with the central portion of the die a receptacle for the material to be pressed into tile.

The objects of the invention are to provide a power tile press embodying novel features of construction which will produce tile of superior quality and with a minimum expenditure of time and labor; to provide novel and improved means for reciprocating the frame as the tile is being pressed; to provide improved means for automatically locking said frame of the lower die as it is depressed by the upper die, so as to hold it down; to provide such means which will operate continuously as the frame is depressed by successive steps; to utilize cams for such locking means; to operate said cams automatically; to lock the cams against operation when the frame is elevated, and to release them by the initial downward movement of the frame; to secure means for causing the upper die to impart to the tile a second blow without rising up out of the frame; to provide supplemental means for finally depressing the frame to release the tile; to restore the frame to its upper position automatically and by springs as soon as it is unlocked from its depressed position; to provide adjustable stop means to determine the upper position of the frame and also its lowest position flush with the central portion of the lower die to discharge a tile; to provide a tile press of the character described embodying a minimum number of simple moving parts which will withstand the wear and action of the dust incident to the manufacture of tile, and to obtain other results and advantages as may be brought out in the following description.

Referring to the accompanying drawings,

in which like numerals of reference indicate the same parts throughout the several views,

Figure 1 is a front elevation of a tile press embodying my invention;

Figure 2 is a transverse vertical sectional view taken on the line 2-2 of Fig. 1;

Figure 3 is a fragmentary view of the lower portion of the press, the lower die and bed of the press being shown in section, and the upper die being shown compressing a tile in the lower die;

Figure 4 is a transverse vertical sectional view taken on the line 4-4 of Fig. 3;

Figure 5 is a horizontal sectional view taken on the line 5-5 of Fig. 1, the lower die, its frame and the bed of the press being shown in plan view;

Figure 6 is a transverse vertical sectional view through the lower part of the press showing the manner of forcing the frame of the lower die downwardly into a position flush with the top of the central portion of said die, and

Figure 7 is a similar view showing the manner of loading the lower die with the material of which the tile are formed.

In the specific embodiment of the invention shown in the drawings, 1 indicates the bed of a press of my improved construction, supported upon suitable legs 2. Upon said bed are spaced uprights 3, 3 between which slides a cross-head 4 carrying the upper die 5. The lower die comprises a central portion 6 fixed upon the bed 1 of the press, and a frame 7 surrounding said central portion and fitting slidably thereon to move up and down. I have shown dies adapted to make one square tile at a time, but it will be understood by those skilled in the art that the shape and number of tiles made at a time are immaterial.

The frame 7 is fixed, as by nuts 8, 9, upon the upper ends of supporting rods 10, 10, which extend slidably downward through spaced guideways at the top and bottom of the bed 1 and extend somewhat below said bed. Normally the frame is held in its uppermost position by helical springs 11, 11, one on each of the rods 10 resting at its lower end on a bearing plate 12 secured to the bottom of the bed 1 and pressing at its upper end against a washer 13 underlying a stop,

such as pin 14, on the rod 10 below the top of the hollow bed. Said springs thus tend always to force the frame upward, and its uppermost position is determined by suitable stops, those which I have shown and prefer to use comprising bolts 15, 15 on opposite sides of each of the supporting rods 10, said bolts being fast in the top of the bed 1 and projecting up through a plate 16 secured to the frame and provided each with a head 17 above said plate. As shown, the plates 16 are on the supporting rods 10, between the frame and one of its clamping nuts 8 and 9, preferably the lower one, and each 15 plate is parallel to the adjacent side of the frame so that its ends project beyond the ear 18 of the frame which takes the supporting rod, to receive the bolts 15, 15, see Figures 4 and 5. Said bolts screw into the bed 1, so 20 that they are adjustable in height to determine the uppermost position of the frame as desired, lock nuts 19 being provided on said bolts to make them fast when adjusted. It will be understood that the uppermost position of the frame is such that it extends 25 above the central fixed portion 6 of the lower die, so as to form therewith a mold or chamber for the "dust" or material to be compressed into tile, as shown in Figure 2.

30 When the upper die 5 descends it first enters the frame 7 enough to seal the top of the said mold or chamber formed thereby with the central fixed portion 6, and then further downward movement of said upper die is transmitted to the frame so as to carry that down also as the "dust" or material is compressed into a tile, the parts being at the end of the stroke in the positions shown in Figure 3. For thus moving the frame downward, I provide at the underside of the cross head 4, on opposite sides of the die 5, depending projections 20, 20 of sufficient length to engage the frame 7 and move it as described; preferably, said projections are in 45 the form of bolts, screwed into the base 21 of the upper die and provided with lock nuts 21^a, so that they are adjustable to vary the time of their engagement with the frame as related to the time the upper die enters 50 said frame and thus vary the "seal" above referred to.

When the upper die is raised, after compression of the tile is completed, it is necessary that the frame 7 retain its position, without elevation by the springs 11, 11, or be locked against moving upward, and I accomplish this, automatically, by the following means. Beneath the bed 1 and in line with the depending ends of the frame supporting rods 10, 10, (one of them being apertured for the purpose, see Figures 3 and 4), is a horizontal shaft 22, mounted in bearings 23, 23 depending from the bearing plate 12 and a bearing 24 in one of the legs 2, so as

to project at the side of the press. This 65 shaft 22 has fast upon itself wedging cams 25, 25, one adjacent each of the depending supporting rods 10, 10 and having a shoulder 26 overlying a roller 27 laterally projecting from the end of the rod, see Figures 3, 4 70 and 6. Each shoulder has at one end a pocket 28 in which the roller 27 of its adjacent supporting rod is caught when the frame is normally elevated by its springs 11, 11, and the end of the cam shaft 22 which projects at the side of the press has a lever 29 with a weight 30 which tends to turn the cams so that the pockets 28 leave the rollers 27 and eccentric portions 31 of the shoulders 26 engage said rollers. Thus when the frame 75 is forced down by the upper die as it forms the tile, as described above, the said eccentric portions 31, which are of increasing radial distance, wedgingly engage the rollers and hold the frame down when the upper die 80 is raised. It will also be noted that this locking action takes place automatically, by virtue of the weight 30.

After the upper die is raised, upon completion of the compression of the "dust" or 90 material into a tile, it is necessary to further depress the frame 7 the thickness of the tile, or until the top of the frame is flush with the top of the central portion 6 upon which the tile lies, in order to discharge said tile, 95 and this I do by the power of the press through the introduction of some supplemental means between the upper die and the frame 7, so that the pressure is transmitted to said frame without the pressed tile receiving any. As an illustration of such means, I have shown a loading box 32, containing "dust" or material to fill the lower die resting upon a shelf 33 on the front of the frame 7, see Figures 2, 5, 6 and 7, the 100 sides of this loading box, at its end next the press, being provided with arms 34, 34 which lie at their free ends upon the sides of the frame 7, as shown in Figures 2 and 5. The operator, when he is ready to finally depress the frame to discharge the tile, pushes the loading box 32 toward the press enough to cause the ends of the arms 34, 34 to underlie the bolts 20, 20 on the upper die, and then upon again bringing down said upper die 110 the frame 7 will be further depressed by said bolts striking said arm ends resting upon the frame, as shown in Figure 6. Of course the ends of the arms must be thick enough so that the upper die will not touch the tile 115 at this time, and as the frame lowers the cams 25 automatically lock it down there, so the upper die can be raised at once. This final position of the frame 7 is preferably determined by adjustabl stops, which I have 120 shown as bolts 35, 35 projecting from the top of the bed 1, into which they screw, and provided with lock nuts 36, 36.

With the frame flush with the central portion of the lower die, and both flush with the shelf 33, the operator slides forward the loading box 32 until it registers with the central portion of the die, as shown in Figure 7, the front end of said box pushing the compressed tile onto a conveyor 37 which carries it off, said conveyor being also flush with the top of the frame, central portion and shelf. 5
10 Then the operator raises the weighted lever 29, and allows the springs 11, 11 to automatically elevate the frame 7 to its normal position, the rollers 27 entering the cam pockets 28 so that the frame is locked in such elevated normal position and the cams are idle. This upward movement of the frame 7 carries the loading box with it and the "dust" or material in said box drops through its mesh bottom and fills the mold or chamber 15 of the lower die formed by the elevated frame with the fixed central portion. The loading box is then withdrawn onto the shelf 33 again, and the press is ready to operate to compress another tile in the same manner as has been described. 20
25

The upper die 5 of my improved tile press can be reciprocated by any suitable means adapted to cause said upper die to strike percutient blows upon the material in the lower die, although I have shown the cross head 4 which carries it secured to the screw 38 of a percussion screw press of a suitable and well-known type adapted to be operated by power. It has been found that two blows 30 upon the "dust" or material being formed into a tile are desirable to properly compress the same and expel the air, and, as the upper die must not be withdrawn from the frame of the lower die for the second blow, I have 35 provided means by which the said screw 38 can move independently of the upper die and far enough to withdraw upwardly after the first blow and descend upon the upper die with a second blow. Referring to Figure 40
45 2 it will be seen that I have provided the screw 38 with an enlarged head 39 which lies in a cylindrical socket 40 in the cross head 4 and is held against withdrawal by a keeper plate 41, forming a swivel connection. 50
55 The head 39 thus has a limited movement independent of the cross head, and for the second blow the screw is withdrawn for not more than this limited distance and then brought down again against the bottom of the socket 40. This enables a second blow 60 to be struck without breaking the "seal" formed by the upper die with the frame 7, and yet said upper die can be moved up and down with respect to the lower die, when desired, as usual. 65

While I have shown and described one possible embodiment of my invention, it will be understood that this is for the purpose of illustrating the principles thereof only, and

it will be obvious that many modifications 65 and changes can be made in the detail construction of my press and its various parts by those skilled in the art without departing from the spirit or scope of the invention. Therefore, I do not desire to be limited in 70 the construction and use of my invention except as required by the following claims when construed in the light of the prior art. 75

Having thus described the invention, what I claim is:

1. In a power tile press, the combination of a lower die to receive the material of which the tile is to be formed, an upper die adapted to cooperate with said lower die to compress the material, operating means 80 for moving the upper die into and out of contact with material in the lower die, and means for enabling successive percutient blows to be struck upon the material while the dies are in contact therewith. 85

2. In a power tile press, the combination of a lower die to receive the material of which the tile is to be formed, an upper die adapted to cooperate with said lower die to compress the material, operating means for 90 moving the upper die into and out of contact with material in the lower die, and means for striking successive percutient blows upon one of said dies while in contact with the material. 95

3. In a tile press, the combination of a lower die to receive the material of which the tile is to be formed, an upper die adapted to cooperate with said lower die to compress said material, a power element to move the upper die into and out of engagement with the lower die, and means for connecting the power element to the upper die so that said power element may exert a percutient blow upon said upper die without retraction 100 of said upper die. 105

4. In a tile press, the combination of a lower die to receive the material of which the tile is to be formed, an upper die adapted to fit into said lower die to compress the material, operating means for moving the upper die into and out of the lower die, and means for exerting successive percutient blows upon said material while the upper die remains in contact with the material. 110

5. In a tile press, the combination of a lower die to receive the material of which the tile is to be formed, an upper die adapted to cooperate with said lower die, a reciprocating element connected with the upper die for causing it to strike percutient blows upon material in said lower die and having a limited movement independent of said upper die, and means for reciprocating said element. 115
120

6. In a tile press, the combination of a support, a lower die mounted on said support to receive the material of which the tile

is to be formed, an upper die adapted to cooperate with said lower die, a screw threaded in said support, said screw having a swivel connection with the upper die to move it into and out of the lower die, said swivel connection allowing the screw to move longitudinally independent of the upper die, and means for rotating said screw.

7. In a tile press, the combination of relatively movable lower die members cooperating to receive the material to be compressed, an upper die cooperating with said lower die members to move them one with respect to another and compress the material, means for actuating said die members into normal position, means for exerting successive percutient blows upon said upper die while in contact with the material, and means for automatically locking the lower die members in the relation into which they are moved by each of said blows.

8. In a tile press, the combination of relatively movable cooperating die members to receive the material to be compressed, means for actuating said die members into normal position, means cooperating with said die members to compress said material, said means moving said die members out of normal position, and means for holding said die members in said last-mentioned position against said actuating means for moving the said die members into normal position.

9. In a tile press, the combination of relatively movable cooperating die members to receive the material to be compressed, means cooperating with said die members to compress said material, said means causing relative movement of said die members during the pressing operation, and means for automatically locking said die members in the relation to which they are so moved.

10. In a tile press, the combination of relatively movable cooperating die members to receive the material to be compressed, means cooperating with said die members to compress said material, said means causing relative movement of said die members during the pressing operation, and means for positively holding said die members in the position to which they are moved, said holding means being automatically thrown into operation by relative movement of said die members.

11. In a tile press, the combination of relatively movable cooperating die members to receive the material to be compressed, means cooperating with said die members to compress said material, said means causing relative movement of said die members during the pressing operation, locking means for holding said die members in the position to which they are moved, and means for normally maintaining said locking means in inoperative position and throwing the same

into operative position upon said relative movement of said die members.

12. In a tile press, the combination of relatively movable cooperating die members to receive the material to be compressed, means cooperating with said die members to compress said material by successive blows, said means causing relative movement of said die members during the pressing operation, and locking means for holding said die members in the position to which they are moved and allowing them to move further.

13. In a tile press, the combination of relatively movable cooperating die members to receive material to be compressed, means cooperating with said die members to compress said material, said means causing relative movement of the die members during the pressing operation, and a cam for locking the moving die member as it is moved.

14. In a tile press, the combination of relatively movable cooperating die members to receive material to be compressed, means cooperating with said die members to compress said material, said means causing relative movement of the die members during the pressing operation, and a gravity operated cam for locking the moving die member as it is moved.

15. In a tile press, the combination of relatively movable cooperating die members to receive material to be compressed, means cooperating with said die members to compress said material, said means causing relative movement of the die members during the pressing operation, a cam for locking the moving die member as it is moved, and a weighted hand lever for operating said cam.

16. In a tile press, the combination of relatively movable cooperating die members to receive the material to be compressed, means cooperating with said die members to compress said material, said means causing relative movement of said die members during the pressing operation, a cam for locking the moving member as it is moved and normally held in inoperative position by said member, and means for automatically throwing said cam into operation upon said relative movement of said die members.

17. In a tile press, the combination of relatively movable cooperating die members to receive the material to be compressed, means cooperating with said die members to compress said material, said means causing relative movement of said die members during the pressing operation, a cam locking the moving member as it is moved and normally held in inoperative position by said member, and gravity operated means for swinging said cam into operative position upon relative movement of said die members.

18. In a tile press, the combination of relatively movable cooperating die members to

receive the material to be compressed, means for actuating said die members into normal position, means cooperating with said die members to compress said material, said 5 means moving said die members out of normal position, a cam for locking the moving member as it is moved and normally held in inoperative position thereby, and means for throwing said cam into operative position 10 upon movement of said die members to hold the said die members against the action of said actuating means for moving the die members into normal position.

19. In a tile press, the combination of relatively movable cooperating die members to receive the material to be compressed, means for actuating said die members into normal position, means cooperating with said die members to compress said material, said 20 means moving said die members out of normal position, a cam having a pocket, an element on the moving die member engaging said cam and normally lying in said pocket said element adapted to leave said pocket 25 upon relative movement of the die members, and means for automatically moving the cam into engagement with said element.

20. In a tile press, the combination of a lower die having a movable frame, an upper 30 die adapted to depress said frame, rods extending from said frame slidably into the bed of the press, springs on said rods normally holding the frame upward, cams arranged and adapted to hold the rods down as 35 they are depressed, and means for automatically operating said cams as the frame is depressed.

21. In a tile press, the combination of a lower die having a movable frame, an upper 40 die adapted to depress said frame, rods extending from said frame slidably into the bed of the press, springs on said rods normally holding the frame upward, a cam shaft projecting at one side of the press, 45 cams on said shaft arranged and adapted to hold the rods down as they are depressed, and a weighted lever on said shaft for automatically engaging said cams as the frame is depressed.

50 22. In a tile press, the combination of relatively movable cooperating die members to receive the material to be compressed, means cooperating with said die members to compress said material, said means causing 55 relative movement of said die members during the pressing operation, and means actuated by said die cooperating means for causing further relative movement of said die members in the same direction.

60 23. In a tile press, the combination of relatively movable lower die members to receive the material to be compressed, an upper die to cooperate with said lower die members, said upper die causing relative

movement of said lower die members during 65 the pressing operation, and means adapted to be interposed between said upper die and lower die members for causing further relative movement of said die members in the same direction. 70

24. In a tile press, the combination of relatively movable cooperating die members to receive the material to be compressed, means cooperating with said die members to compress said material, said means causing relative movement of said die members during the pressing operation, a loading box for filling the die members with material, and means on said loading box adapted to be actuated by said die cooperating 80 means to cause further relative movement of said die members in the same direction. 85

25. In a tile press, the combination of a lower die having a movable frame, an upper die adapted to cooperate with said lower die and depress said frame, a loading box movable up and down with said frame and movable toward and away from the frame horizontally, and means on said loading box to be projected between the upper die and 90 frame to cause further downward movement of the frame when the upper die is again lowered.

26. In a tile press, the combination of relatively movable die members forming a die chamber to receive the material to be compressed, a cooperating die adapted to enter said die chamber and to cause relative movement of said die members, and adjustable means for limiting the entry of said 100 cooperating die into said die chamber. 95

27. In a tile press, the combination of relatively movable die members forming a die chamber to receive the material to be compressed, a cooperating die adapted to 105 enter said die chamber and to cause relative movement of said die members, and adjustable stops on the bed of the press for limiting said relative movement of the die members. 110

28. In a tile press, the combination of a lower die having a movable frame, an upper die adapted to cooperate with the lower die and move said frame downward, and means adjustably connecting said frame to the bed 1 of the press to limit its upward movement.

29. In a tile press, the combination with a lower die having a movable frame, supporting rods extending from said frame slidably into the bed of the press, a cross plate on each of said supporting rods adjacent the frame, and bolts extending slidably through the opposite ends of each of said cross plates and threaded into the bed of the press, whereby upward movement 1 of the frame can be adjustably limited.

30. In a tile press, the combination of relatively movable cooperating die members

6 to receive material to be compressed, means cooperating with said die members to compress said material, said means causing relative movement of the die members during the pressing operation, and an automatically operating cam for locking the moving die member as it is moved.

31. In a tile press, the combination of relatively movable cooperating die members

to receive material to be compressed, means 10 cooperating with said die members to compress said material, said means causing relative movement of the die members during the pressing operation, a wedging cam for locking the moving die member as it is 15 moved, and means for automatically engaging said cam.

EDMUND W. ZEH.
